TENT FRAME

Edgar Herbert Hoskins, Davis, Calif., assignor of one-half to Thomas E. Hoskins, Grass Valley, Calif.

Application November 6, 1956, Serial No. 620,753

4 Claims. (Cl. 135—3)

The present invention generally relates to a novel concept in the construction of a tent and more particularly to a novel tent frame which is easily collapsible and disassembled for easy transport and storage but yet which is extremely sturdy in construction and provides an easily assembled tent frame which is automatically adjusted to tents with certain variations in size and which may be manually adjusted for substantially all size tents of the type generally known as an umbrella-type or pyramidal type.

One of the major problems in setting up the tent such as those used by hunters, campers or other persons is the support of the various portions of the tent under various weather conditions and still maintain a dependability as well as ease of assembly and disassembly. One of the problems encountered is the size variations of the tent itself both from a manufacturing standpoint and also from the standpoint of shrinkage and stretching or enlargements caused by change in the moisture content of the canvas itself. Also the tent frame must be sufficiently strong to withstand certain wind loads and also to provide a rigidity sufficient for support of the tent under various conditions. Accordingly, it is the primary object of the present invention to provide a tent frame which will solve the above-mentioned problems connected with tent constructions and also provide a tent frame which is extremely lightweight in construction and provided with a multiplicity of readily detachable elements all of which may be easily assembled and disassembled at the point of erection of the tent thus enabling the tent to be easily assembled and disassembled by a single person and which when completely assembled will provide the interior of the tent with no obstructions, such as a center pole in the interior of the tent thus permitting efficient utilization of the interior area thereof.

Other objects of the present invention will reside in its simplicity of construction, extreme ease of assembly adaptation for various sized tents and automatic adjustment for shrinkage and enlargement caused by rain or dry weather and the qualities which permit the tent frame to be readily adapted to its particular purpose.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of a tent employing the tent frame of the present invention;

Figure 2 is a detailed sectional view of the cross bar construction;

Figure 3 is a detailed sectional view of a supporting leg;

Figure 4 is a detailed sectional view of the peak post;

Figure 5 is a detailed sectional view of the leg taken substantially along section line 5—5 of Figure 6; and

Figure 6 is a perspective view of the tent frame with the tent being shown in phantom.

Referring now specifically to the drawings, the numeral 10 generally designates the tent frame of the pres-

2

ent invention which includes a first cross bar generally designated by the numeral 12 and a second cross bar generally designated by the numeral 14 each of which includes a depending post of leg 16 at each end thereof with each of the posts or legs 16 being identical and each of the cross bars 12 and 14 being identical.

The cross bars 12 and 14 are disposed in intersecting relation with one being disposed immediately above the other. Each cross bar includes an elongated tubular member 18 adjustably receiving a smaller tubular member 20 having a plurality of transverse apertures 22 receiving a fastening pin 24 therethrough for effectively adjusting the length of the cross bar. The other end of the tubular member 18 telescopically receives a third tubular member 26 disposed in abutting engagement with a compression coil spring 28 disposed within the tubular member 18. A plug 30 is also disposed in the tubular member 18 and is provided with a slot 32 receiving an eye 34 on the end of the spring 28 with a fastener 36 extending transversely of the slot 32 and through the eye 34 for securing the spring 28 to the plug 30 which in turn is secured to the sleeve 18 by inwardly extending indentations 38 which effectively hold the wood plug 30 within the sleeve 18 and prevents the spring 28 from sliding outwardly of the sleeve 18.

The outer ends of the tubular member 20 and the tubular members 26 is provided with an end adapter 40 which is provided with a reduced portion 42 having a shoulder 44 thereon with a projecting longitudinal pin 46 for reception in a grommet 48 in the tent cover which is generally designated by the numeral 50. On the underside of each of the adapters 40 is a generally spherical projection 52 in detachable frictional engagement with an upper tubular member 54 forming a portion of one 30 of the legs 16 thus detachably connecting the legs 16 to the cross bars 12 and 14 inwardly of the longitudinal pin 46 thus disposing the legs 16 inwardly of the corner of the tent cover 50 and generally in contact with the corners thereof. The spherical projection 52 and the inclined upper edge 56 of the upper tubular member 54 will permit variation in the angle of the legs 16 thus permitting the legs 16 to be intimately disposed against the inside corner of the tent cover. Inasmuch as the cross arms 12 and 14 are independent of each other, these arms may readily adapt themselves to various shapes 45 of tent covers in which the grommets 48 are arranged at the upper corners thereof. The upper tubular member 54 of each leg 16 is slidably received in a larger tubular member 58 having a spring and plug therein 50 which is identical to that described in connection with the cross bar 12. The lower end of the enlarged tubular member 58 receives a smaller tubular member 60 having a plurality of apertures 62 thereto for receiving the transverse fasteners 64 for providing an initial adjustment 55 of the leg 16 so that the spring disposed between the plug or block 30 in the tubular member 58 may effectively urge the upper tubular member 54 upwardly whereby the rubber foot 66 will engage the bottom of the tent cover for urging the same away from the cross arms 60 thus tensioning the side walls of the tent cover in such a manner that they will be maintained in a taut or unwrinkled condition.

Extending upwardly from the cross bars 12 and 14 is a peak pole 68 incorporating in its construction a tubular member 70 telescopically receiving a wooden rod 65 72 having a projecting pin 74 on the upper end thereof. The tubular member 70 is provided with a compression coil spring identical to coil spring 28 and designated by the same numeral with a plug 30 being disposed therein and connected to the spring 28 in the identical manner. An adapter 74 is disposed in the lower end of the tubular member 70 and has a generally semi-cylindrical

lower surface designated by the numeral 76 forming a saddle for engagement over the upper of the cross bars and specifically for engagement with the central tubular portion 18 thereof. A screw fastener 78 is provided for securing the adapter 74 to the plug 30 thus retaining the peak pole 68 in position and maintaining the roof portion of the tent cover in position.

The roof portion of the tent cover 50 includes four generally triangular members 80 which are joined by a grommet 82 at the peak thereof for receiving the projecting pin 74 and an overlying closure member 84 is provided for the grommet 82 thus providing a waterproof roof 80. Four side walls 86 are provided each of which are generally trapezoidal and substantially equal in construction and provided with one of the walls 86 being provided with an opening and closure therefor designated generally by numeral 88. The side walls 86 are interconnected by a bottom wall 90 together with a projecting flange or seam portion 92 having a plurality of eye members 94 for receiving the tent pegs 96 which holds the bottom 90 down.

With the feet 66 in engagement with the bottom 90 and the pins 46 in engagement with the grommets 48 and the pin 74 in engagement with the grommet 82, the springs and each of the component elements will urge all of the corner points of the tent cover outwardly or oppositely from each other thus tensioning the tent cover 50 but still permitting the same to give under a wind load or to give when shrinkage occurs but also permits automatic expansion thereof for taking up any slack thus preventing any flapping or wind damage caused by such flapping. The construction also eliminates any center pole construction thus providing the interior free of obstructions and the device is constructed of tubular metallic members of lightweight construction such as aluminum which renders the device easy to assemble and disassemble. In actual practice, the entire tent cover may be unrolled and the frame assembled therewith and ready for occupancy within a matter of several minutes.

When thin tubular members are employed, a cap 39 may be employed in the inner end of member 26 to assure that the spring 28 will enter the end of member 26. It is also contemplated that other spring arrangements may be employed by rearranging the elements. As an example, the spring could be disposed exteriorly of the central member with the outer tubular members telescoping over the central member.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A tent frame for a substantially pyramidal shaped tent cover having a bottom, upwardly extending side walls, a top and an entrance closure, said frame comprising a pair of longitudinally adjustable independent cross bars arranged in intersecting relation, means on each end of each cross bar for detachable engagement with the diagonally opposed upper corners of the tent cover, a longitudinally adjustable depending leg detachably and pivotally connected to each end of each cross bar adjacent the means for engagement with the tent cover, said legs adapted to engage the tent cover on the inner surface of each corner edge and terminating in the lower corner thereof, a peak pole detachably engaged with the upper cross bar at the point of intersection of the cross bars, means on the upper end of the peak pole for engagement with the peak of the top of the tent cover, said cross bars and legs being constructed of telescopic members resiliently urged outwardly for maintaining the tent cover in taut condition and permitting the frame to 75

be employed in tent covers of different sizes, each end of each cross bar including a depending generally spherical projection, each of said legs having a tubular upper end in detachable frictional engagement with the spherical projection whereby the depending legs may swivel universally in relation to the cross bars for intimate engagement with the corners of the tent cover.

2. In a tent construction including a tent cover having a bottom, upwardly converging side walls, a peaked top and an entrance closure in one side wall; a collapsible frame for holding said tent cover in taut condition at all times comprising a pair of cross bars of longitudinally adjustable construction, a depending leg adjacent each end of each bar, means detachably and swivelly connecting each leg to the end of a bar, each leg being longitudinally adjustable and including a protective foot on the lower end thereof for engagement with the lower corners of the tent cover, projection means on the outer end of each bar for engagement with the tent cover, a peak pole extending upwardly from the point of intersection of the cross bars to the peak of the tent cover, said peak pole, each cross bar and each leg including longitudinally telescopic sections with means locking the sections in longitudinally adjusted position, said cross bars and legs having spring means between adjacent sections urging said sections in extended relation for continuously tensioning all portions of the tent cover during size changes caused by change in moisture content of the tent cover material.

3. A tent frame for pyramidal tent covers having a bottom, upwardly extending side walls and a peaked top, one side wall of the tent cover having an entrance opening with a closure therefor, said frame including a pair of independent cross bars arranged in intersecting relation with the point of intersection being disposed below the center of the peaked top of the tent cover, outwardly projecting means on each end of each cross bar for detachable engagement with the upper corners of the tent cover, a depending projection at each end of each cross bar, an elongated leg adapted to be disposed in each corner edge of the tent cover, the lower end of the legs engaging the bottom corners of the tent cover, the upper end of each leg including a tubular socket frictionally and detachably receiving a depending projection on the cross bar, said depending projections having rounded surfaces permitting limited swinging movement of the legs whereby the legs may be accurately positioned in the corner edges of the tent cover, each of said cross bars and legs being sectional and longitudinally adjustable in length, spring means urging one section of each cross bar and leg outwardly thereby allowing for shrinkage and maintaining the tent cover taut during changes in size, and a peak pole extending vertically from the point of intersection of the cross bars, said peak pole being longitudinally adjustable and including a projection for engaging the center of the peaked top, said peak pole including a downwardly facing U-shaped saddle freely resting on the upper cross bar for detachable engagement with the upper cross bar thereby supporting the peak pole from the cross bars and leaving the area below the cross bars free of obstructions.

4. The combination of claim 3 wherein the lower end of each leg is provided with a rounded resilient foot for engaging the lower corner of the tent cover and preventing damage to the tent cover.
